[57] CLAIM

The ornamental design for an anti-slip picture wire hanger bracket, as shown and described.

DESCRIPTION

FIG. 1 is a front elevational view of an anti-slip picture wire hanger bracket, showing my new design;
FIG. 2 is a right side view thereof at an enlarged scale, the left side view being symmetrical;
FIG. 3 is a top plan view thereof, at the scale of FIG. 1;
FIG. 4 is a bottom plan view thereof; and
FIG. 5 is an isometric view thereof.
